UNITED STATES PATENT OFFICE.

FREDERICK G. SHERBONDY, OF AKRON, OHIO, AND MAX E. BOEHM, OF APPLETON, WISCONSIN.

METHOD OF BLEACHING WOOD PULP.

Application filed February 21, 1925. Serial No. 10,811.

The object of our invention is to provide a novel apparatus and method for bleaching, under pressure, wood pulp at a high consistency, the invention being adapted, however, for use in connection with the bleaching of other materials.

More specifically, the method resides in agitating and mixing the stock, at high consistency, and under pressure, with the bleach liquor, in a closed container, without the application of heat; and, by this cold bleaching, under pressure, of the stock, at a high consistency, a much tougher grade of work is secured than is possible in hot-bleaching, which has a tendency to weaken the fibres of the stock. Another advantage of this method of bleaching in a closed, air-tight container, is that escape of chlorine gas is prevented, thereby economizing in the cost 20 of practising the method.

The apparatus resides in a closed container or retort, which is constructed so as to be pressure tight and thus retain all the chlorine gases, and whereby the pressure of the gases evolved in the retort makes it possible to secure a better penetration of the bleach liquor into the stock. The invention also resides in providing the retort, interiorly, with baffles, so arranged that it is possible 30 to thoroughly mix the stock at a high consistency.

An apparatus capable of practising the method is disclosed in the accompanying drawings, in which like reference-characters 35 denote corresponding structural parts in the several views. Briefly described:

Figure 1 is a view in side elevation of our retort or engine;

Figure 2 is a view in end elevation thereof; 40 Figure 3 is a view in top plan of the retort removed from its supporting pillars; and

Figure 4 is a view in section, taken upon the plane of the section line 4—4, indicated in Fig. 1, looking in the direction of the 45 arrows shown in connection therewith.

Referring, now, in detail to the drawings: 50 1 indicates, in general, our globe rotary bleaching engine, which is constructed pressure proof and air-tight, so as to prevent escape of chlorine gas in the operation thereof, and which is provided with a man-hole 55 2 tightly closed by a cover 3 when the engine is in operation, and with a valve 4, said cover and valve being preferably disposed at 55 diametrically-opposite points on the engine.

The engine is also provided with trunnions 5, 5, rotatably supported in bearings at the top of pillars 6, 6.

Fast on one of said trunnions is a gear-wheel 7 meshing with a gear-train driven 60 from a suitable source of power, whereby the engine or retort may be revolved at the speed desired.

Interiorly, the globe 1 is provided with equidistantly spaced pairs of wings 8, 8, each 65 pair being, roughly, bow-shaped, as shown. These wings constitute agitators or baffles, which agitate and mix the stock with the bleach liquor. Referring to the drawing it will be seen that the wing-shaped baffles are 70 not all arranged alike, but are so arranged that the point or the apex of adjacent baffles point in opposite directions with respect to the direction of rotation, that is, one set of alternate baffles point in the direction of rotation while the other set of baffles point 75 in the opposite direction to that of rotation. By the construction described, it is possible to expeditiously mix stock, at high consistency, with the bleach liquor, and to carry 80 on the bleaching operation under pressure. This pressure may be gas evolved from the chlorine used in the bleaching liquor, or such pressure may be supplemented, as required, 85 by other forms of gas, or by water, or by steam forced into the rotary bleacher or retort. The action of the apparatus is as follows:

The rotation of the globe tends to raise 90 the pulp on the up-turning side of the chamber and to cause it to flow back towards the lowermost point of the globe. This causes the pulp to move continuously in a rolling or tumbling flow in the same direction, which 95 is effective in causing a thorough mixing of the stock and liquor. The baffles assist in raising the stock from the bottom of the globe, but in addition, they are so arranged as to cause alternate concentrating and spreading of the flow. It will be seen that 100 as a baffle pointing away from the direction of rotation passes through the stock, it will carry a portion of the mixture along in front of it, and as it begins its upward travel the sides of the baffle form a pocket-like element and direct the flow towards the point of the baffle, where it will pass over the upper edge in a concentrated stream. But 105 with respect to an adjacent baffle, the sides will act as deflectors for the stream and will 110

cause the stock to spread out and pass over the upper edge of the baffle in a more or less evenly distributed manner. It will be noted that since adjacent baffles are reversed with respect to each other the flow of the mixture is subjected to alternate concentration and dispersion.

It will be seen that, by our method and apparatus, greatly improved results are obtained. By reason of bleaching, under pressure, in a closed retort, there is no loss of the bleach liquor or gases, resulting in a substantial saving over customary methods of bleaching in an open receptacle. Since the retort is pressure-proof, the gases generated in the bleaching operation are confined and the pressure thereof makes it possible to get a better penetration of the liquor into the stock.

Having thus fully described our invention, what we claim as new and desire to secure by Letters-Patent of the United States is:

1. The method of bleaching pulp which consists in enclosing a mixture of pulp and bleaching liquor within a sealed spherical container, and agitating the mixture by subjecting it to alternate spreading and concentrating flow action.

2. The method of bleaching pulp which consists in enclosing a mixture of pulp and

bleaching liquor within a sealed container, agitating the mixture by causing it to flow continuously in one direction with alternate spreading and concentrating action.

3. The method of bleaching pulp which consists in enclosing a mixture of pulp and bleaching liquor within a sealed spherical container, and agitating the mixture by subjecting it to a rolling flow towards a common point.

4. The method of bleaching pulp which consists in admitting a mixture of pulp and bleaching liquor to a spherical chamber, sealing the chamber, subjecting the mixture to pressure, agitating the mixture by rotating the chamber and causing the flow of the mixture to alternately spread and concentrate.

5. The method of bleaching pulp which consists in admitting a mixture of pulp and bleaching liquor to a spherical chamber, sealing the chamber, subjecting the mixture to pressure, agitating the mixture by rotating the chamber continuously in one direction and causing the flow of the mixture to alternately spread and concentrate.

In testimony whereof, we affix our signatures.

FREDERICK G. SHERBONDY.
MAX E. BOEHM.
